UNITED STATES PATENT OFFICE.

ERNEST A. OAKES, OF SEYMOUR, CONNECTICUT.

DIE-STOCK.

1,154,424.

Specification of Letters Patent. Patented Sept. 21, 1915.

Application filed January 13, 1914. Serial No. 811,846.

To all whom it may concern:

Be it known that I, ERNEST A. OAKES, a citizen of the United States, residing at Seymour, in the county of New Haven and State of Connecticut, have invented certain new and useful Improvements in Die-Stocks, of which the following is a specification.

This invention relates to die-stocks.

10 The die-stock of ordinary type involves in its make-up an annular body provided with one or more handles and is adapted to hold interiorly thereof several chasers. In use this annular body with the inclosed 15 chasers, receives within it the work and by turning the body the chasers form on the work, a thread. After the thread is made there will be found on the work burs or protrusions between the chasers and the 20 latter being rigidly mounted are frequently seriously injured and at times irreparable damage is done to their cutting edges by these burs. To eliminate this disadvantage I provide for retractive or backing-off movement of the chasers, so that when the improved tool has performed its office of cutting a thread, it can be readily and easily taken from place without possibility of the burs mentioned affecting in any wise the 25 cutting edges of the chasers or of the chasers injuring the formed thread.

The invention comprises other features of novelty and advantage which with the foregoing will be stated at length in the following description wherein I will set forth in full that one of the several forms of embodiment of the invention which I have selected for illustration in the drawings accompanying and forming part of the present specification. From this it will be clear that I do not restrict myself to such showing; I may depart therefrom in material respects within the scope of the invention defined by the claims following said description.

45 Referring to said drawings: Figure 1 is a top plan view of a die-stock involving my invention. Fig. 2 is a side elevation partly in section of said die stock, the section being on the line 2—2 of Fig. 1. Fig. 3 is a section on the line 3—3 of Fig. 4, and, Fig. 50 4 is a section on the line 4—4 of Fig. 3.

Like characters refer to like parts through-

out the several figures, which it will be noted are on different scales.

55 My die stock comprises in its make-up a suitable body, that designated by 2 answering satisfactorily in this connection, being annular and thus conforming in its general shape to those now in common use. The 60 body 2 has circumferential complemental sockets 3 to removably receive the handles 4 which provides a simple way of revolving or rotating the body or head 2; this in fact is the customary manner of performing 65 this function with existing die-stocks.

There is carrying means for the chasers and said carrying means may vary in nature, although the member 5 satisfactorily meets the desired conditions, said carrier as 70 shown consisting of a circular plate or disk which has a bearing or sliding fit against the circular inner surface 6 in the central opening of the head or body 2. From this it will be clear that the chaser-carrier 5 can 75 be turned in said body 2, and the reason for this will be hereinafter explained. The chaser-carrier 5 as illustrated, is shown equipped with four chasers or as they are some times termed "lands" 7, but their 80 number is not a matter of consequence nor is their particular shape material, the invention as will be inferred not residing in any particular form of chaser but rather as to one of its features, in a highly advanced 85 advantageous means for effecting backing off movement thereof when occasion requires. As shown the carrier 5 has radial slots 9 corresponding in number with and adapted to receive the respective chasers 7. The 90 outer ends of these slots 9 intersect the cylindrical chambers 10 which open into the periphery of the carrier 5, while the inner ends thereof connect with the central work-receiving opening 11 of the carrier, to permit the cutting-portions of the chasers 7 to be projected into said opening and to also permit said cutting portions to act on the periphery of said work.

The circular surface 6 to which I have referred, is interrupted at intervals by relief notches 12 which correspond in number with the chasers and which present one of several convenient ways of permitting retractive movement of said chasers, said movement in the present case being in an out-

ward direction. Each of the notches or reliefs 12 has a beveled portion 13 extending from the bottom thereof toward the surface 6, and the purpose of which will hereinafter be set forth.

In the chambers 10 are comparatively freely or slidingly mounted what I term "plungers" 14, consisting as illustrated of cylindrical sleeves internally threaded to receive the respective bearing and adjusting screws 15 against which the base of the respective chasers 7 constantly abut, each sleeve having diametrically-opposite slots in its inner edge to receive the base portion of its chaser. By running these screws 15 in or out the respective chasers 17 can be adjusted to regulate the depth of cut. It will be clear, therefore, that the chasers can be independently and readily adjusted. To provide for easy access to them without dismounting anything, I may, as shown, form in the body 2 holes 7' to receive a suitable implement to turn the screws 15 the slots of which are opposite the holes 7' when the carrier 5 is in its normal position. The plungers or sleeves 14 are circumferentially cut away as at 16 which leaves abutments as 17 at the inner ends of said plungers. The carrier 5 is transversely perforated as at 18 to receive the pins 19 which are driven into place and which extend transversely through the cut away portions or keyways 16. These pins constitute suitable stops for the respective plungers or sleeves 14, being so positioned as not to prevent the movement necessary to effect retraction of the chasers 7 as will hereinafter appear, but they do prevent accidental displacement or falling out of the chasers by the abutments or catch portions 17 engaging the same. These pins, however, do not prevent free movement when necessary of the plungers 14. The carrier 5 has segmental apertures 20 to receive springs as 21 which have bearing engagement respectively against the inner arcuate walls of said apertures 20, the springs between their ends extending through notches 22 in the respective chasers 7. Normally or when the chasers 7 are in their advanced or inner positions at which time the plungers 14 are out of the relief notches 12 and against the solid part of the surface 6, these springs 21 will be bowed and will thus exert a constant tendency to retract the chasers 7 or move them and the plungers 14 connected therewith in a radial outward direction. This particular movement is prevented as long as the plungers 14 are against the uncut part of the surface 6.

It will be assumed that the outer ends of the plungers 14 are against the uncut part of the wall 6, and in this event as will be clear the chasers 7 will be in their advanced positions. To effect retraction of the chasers

it is necessary to turn the carrier 5, and for this purpose said carrier may be provided with a handle 23 extending circumferentially from the projecting hub 24 of said carrier. The hub 24 has a guide opening 24' for the work and its inner circular wall merges into the beveled interior surface 5' of the carrier, thereby presenting a chip-receiving chamber.

The parts are shown as occupying their normal or working positions in Fig. 1 the handle 23 at this time being in longitudinal alinement with the adjacent socket 3 and handle 4. To effect backward movement of the chasers the following procedure may be adopted. The handle will be grasped and swung in the direction of the arrow which moves the carrier therewith and shifts the chasers 7 and plungers 14 laterally to carry the plungers into contact with the beveled faces 13 along which they are moved by the springs 21, this action continuing until the plungers are against the bottoms of the reliefs 12 at which point the chasers will have been fully retracted to thus permit the tool being removed from the work without possibility of the work injuring the chasers or the chasers affecting the work. To return the chasers to their operative relations the handle will be returned to the position it is shown as occupying in Fig. 1.

It will be noted that the carrier 5 with the chasers supported thereby presents a unit, being capable of introduction into and removal from the body or head 2 as such which is a point of prime advantage. To hold the carrier 5 and connected parts in place, the tubular nut 25 may be utilized, the threads of which engage corresponding threads on the enlarged portion 26 of the central opening of the body or head 2, the outwardly projecting annular flange 27 of the nut fitting an annular rabbet 28 in said opening. The nut is provided with inwardly extending ears 29, the carrier 5 having practically similar outwardly extending ears 30. It will be understood that when the ears 29 overlie the ears 30 the nut is holding the carrier in place. By turning the carrier sufficiently to bring its lugs or ears 30 opposite the spaces between the lugs or ears 29, said carrier with its chasers can be easily lifted from place for any desired purpose.

The head or body 2 is provided with suitable means for driving the chaser carrier 5, and although said means may vary as to character that shown and now to be described is quite satisfactory. The external bead 3' of one of the sockets 3 (that to the right in Figs. 1 and 2) is notched to produce the shoulder 23' to engage against the free portion of the handle or lever 23 so that when the head or body 2 is turned in the direction of the arrow in Fig. 1, the

shoulder or driving face 23' acting against said lever 23 constituting a rigid part of the carrier 5 will cause the latter to turn in the same direction in which said head or body is turned.

What I claim is;

1. A die-stock comprising a body, a carrier in the body having a central opening and also having chambers opening into the 10 periphery of the carrier, plungers in said chambers, and adjusting screws threaded into said plungers, chasers abutting against the adjusting screws, extending through the carrier into the central opening thereof, the 15 body having reliefs to receive said plungers on a predetermined movement of the carrier, said carrier being turnable in the body whereby the plungers can be moved opposite the reliefs, the body having holes to obtain 20 access to said screws.

2. A die stock comprising a body, a carrier mounted in the body for turning movement, chasers supported by the carrier for movement radially of the body, and springs 25 acting between their ends against the respective chasers, the carrier having apertures to receive the springs, and said springs bearing against the walls of the respective apertures opposite their points of thrust against the 30 respective chasers and tending constantly to move said chasers outwardly, the body having reliefs to receive the chasers when the carrier has been turned a certain distance.

3. A die stock comprising a body, a rocking carrier in the body, chasers supported by the carrier for movement radially of the body, plungers slidingly supported by the carrier, means for preventing rotation of the plungers, and screws tapped into said 40 plungers, for adjusting the respective chasers, the body having reliefs to receive said plungers when the carrier has been turned to a certain position in the body.

4. A die stock comprising a body, a rocking carrier in the body, chasers supported by the carrier for movement radially of the body, plungers slidingly supported by the carrier, means for preventing rotation of the plungers, and screws tapped into said 50 plungers, for adjusting the respective chasers, the body having reliefs to receive said plungers when the carrier has been turned to a certain position in the body,

said body also having openings through it to obtain access to the respective screws.

5. A die stock comprising a body, a rocking carrier in the body, chasers supported by the carrier for adjusting movement toward and from the center of the carrier, means 60 acting against the respective chasers and tending constantly to force them outwardly, the body having reliefs to permit retraction of the chasers when the carrier has been turned in the body a certain distance, and an adjustable support for each chaser mounted 65 on said carrier and movable therewith.

6. A die stock comprising a body, a carrier in the body, chasers adjustably supported by the carrier, and a device for locking the carrier in place in the body and movable on the body without being separated therefrom, to release the carrier and permit the latter being disconnected from the body.

7. A die stock comprising a body, a carrier in the body, chasers adjustably supported by the carrier, and a locking ring 75 fitted in the body having lugs, and intervening spaces, the carrier also having lugs and intervening spaces, the locking ring when its lugs overlie those of the carrier being 80 adapted to hold said carrier in place and said locking ring being turnable in the carrier to move its lugs into registration with the spaces of the carrier to permit the carrier being taken from place without removing the locking ring.

8. A die stock comprising a body, a carrier mounted in the body for turning movement, and having an opening, chasers supported by the carrier for movement toward 90 and from said opening and independently operative springs acting between their ends against the respective chasers, each spring having bearing engagements against the carrier opposite the point where it bears against 95 its chaser, the springs acting constantly to move the chasers away from said opening and the body having reliefs to receive the chasers when the carrier has been turned a certain distance.

In testimony whereof I affix my signature in presence of two witnesses.
